COMMODE

Judson A. Perry, Norfolk, Va., assignor of forty-nine one-hundredths to George D. Whitehurst, Norfolk, Va.

Application July 27, 1938, Serial No. 221,614

13 Claims. (Cl. 4—257)

This invention relates to a toilet fixture and more particularly has reference to a commode device.

Heretofore considerable difficulty has been experienced with commodes, resulting from the fact that the waste pipe frequently becomes clogged or stopped up, and the clearance of such pipe has usually been difficult to effect. While attempts have been made to provide means for clearing waste pipes, the devices heretofore provided have not been satisfactory.

An object of my invention is to provide a means for clearing commode waste pipes that have become clogged.

Another object of my invention is to provide such a device that is relatively inexpensive to manufacture, relatively simple in structure, and easy in operation.

A still further object of my invention is to provide such a means which is relatively inconspicuous, which takes up a minimum of room, and which does not interfere with the normal operation of the commode.

To accomplish the above, and other important objects, my invention in general embraces the concept of introducing into the waste pipe water under sufficient pressure to flush any obstruction therefrom. More specifically my invention includes a device in communication with a water line under the normal city pressure and means for introducing such water under said pressure to the waste line.

In the accompanying drawing there is depicted one embodiment of my inventive concept, it being understood, of course, that various modifications may be made therein without departing from the scope of my invention. In the drawing, in which similar numerals indicate the same parts:

Figure 1 is a top plan view of a device constructed in accordance with my invention, with a portion of the commode being broken away.

Figure 2 is a side elevation of the device shown in Figure 1 with a portion of the commode being broken away.

Figure 3 is a detailed view of the valve construction shown in longitudinal section.

Figure 4 is a cross-sectional view of the valve shown in Figure 3, taken along the line 4—4 of Figure 3.

Referring more particularly to Figures 1 and 2, there is shown a conventional commode designated by the numeral 1, and provided with the usual seat covers 2 and 3, hinged as at 4 to an overhanging lip 5. The lip 5 serves not only as a

base on which to pivot the covers 2 and 3, but preferably projects a sufficient distance to conceal the discharge mouth of my invention.

Water is admitted to the commode through pipe 6, which extends to the usual flush box, and the conventional waste line 7 is provided. However, it will be noted that the commode is cut away around the end of the waste pipe to form a shouldered seat 8 adapted to receive the discharge mouth of my mechanism.

The discharge mouth 9 is preferably cup-shaped and made of rubber or some other material that will form a water-tight seal with the shouldered seat 8. The discharge mouth 9 is mounted upon an arcuate pipe 11 which extends through an aperture 12 formed near the top and at the rear of the commode. A rubber sleeve 13 is fitted in the aperture 12 which, in conjunction with the pipe 11, forms a seal and prevents splashing or overrunning of the water in the commode.

By means of an elbow 14, the arcuate pipe 11 is secured to a section of pipe 15 which, in turn, is threaded in an elbow 16. A pipe 17 is likewise fitted into elbow 16. The pipe 17 is rotatably mounted in bearings 18 and 19, and, as shown in Figure 1, a check valve 21 is interposed in pipe 17. This check valve is adapted to permit the passage of water in only the direction indicated by the arrows in Figure 1, and serves to prevent any counterflow of water.

A bracket 22 is fixedly secured to the rotatable pipe 17 and one end of a lever 23 is pivoted to this bracket. The opposite end of the lever 23 is pivoted to a crank 24, provided at one end with a foot treadle 25 and mounted at its opposite end on a bracket 26 which is secured to the floor.

It will, therefore, be seen that upon actuation of lever 23, the pipe 17 will be oscillated in a counter-clockwise direction which, in turn, will throw the discharge mouth 9 into operative position where it fits into the seat 8 of the waste line, as indicated by the dotted lines in Figure 2. A helical spring 27 is mounted upon pipe 17, so that the discharge mouth 9 will be returned to inoperative position, bearing against the rubber sleeve 13, when the foot is released from the treadle 25.

As shown in Figures 1, 3 and 4, I have provided a conventional type of rotary valve designated generally 28, which is opened when the discharge mouth 9 is in operative position, and thereby admits the water under city pressure to the discharge mouth 9. As best shown in Figure 3, this valve comprises a casing 29 which is securely

mounted upon a section of pipe 31 which is in open communication with the water line of the house. The casing 29 forms a chamber 32 in which there is mounted a stationary wall 33 provided with an opening 34.

The pipe 17 is rotatably journaled, in a watertight fit, within the casing 29, and there is securely mounted upon the pipe 17 a disk 35 provided with an opening 36, which is adapted to 10 register with the opening 34 when the pipe 17 is rotated to operative position. Passages 37 extend through the pipe 17 and the shoulder on the disk 36, so that water admitted through the ports 34 and 36 may enter pipe 17 and pass to the 15 discharge mouth 9.

Of course, it will be obvious that any other type of valve may be used in lieu of the specific valve 28 shown in the drawing.

A second check valve 38 may be placed in line 20 31 to prevent any flow of water from the commode into the main water system of the house. Of course, any number of check valves may be used to insure that there shall be no such counterflow of water, but I have found in actual practice that 25 two have always been sufficient and in most cases a single check valve suffices.

The advantages of my invention are believed to be obvious. The mechanism in general is relatively inconspicuous, and will take up no appreciable space in a bathroom or lavatory. The 30 device is, of course, relatively inexpensive and may be readily operated. By means of this device water under a relatively high pressure, as maintained in most municipal water systems, may 35 be immediately introduced into the mouth of the drain line, and the pressure of this water is sufficient in practically all cases to remove any normal obstructions in such waste line, and to thoroughly flush the line.

40 While I have shown one specific form of structure, it will, of course, be obvious that various modifications may be made in the individual elements and their combined assemblage without departing from the scope of my invention, which 45 is to be determined solely by the appended claims.

I claim:

1. A toilet fixture comprising a commode, a waste line therefor, and means extending through the commode for introducing to said waste line 50 water under a pressure in excess of the hydrostatic head of such water.

2. A toilet fixture comprising a commode, a waste line therefor, a line adapted to carry water under relatively high pressure, and means for 55 simultaneously connecting said pressure line to the waste line, and introducing water under pressure to said waste line.

3. A toilet fixture comprising a commode, a waste line therefor, a line carrying water under 60 relatively high pressure, another line adapted to carry such water, a valve intermediate the two last-mentioned lines, and means for connecting the last-mentioned line to the waste line, and simultaneously opening said valve.

65 4. A toilet fixture comprising a commode, a waste line therefor, a pipe extending into said commode and adapted to be moved into communication with said waste line, said second-mentioned line being connected to a source of water under relatively high pressure, and means 70 for simultaneously moving the second-mentioned line into communication with the waste line and introducing water under pressure to said line.

75 5. A toilet fixture comprising a commode, a waste line therefor, a pipe extending through the

commode, and means for moving said pipe to connect the same with the waste line.

6. A toilet fixture comprising a commode, a waste line therefor, a pipe extending through the commode and in inoperative position having a 5 free end bearing against the wall of the commode, a valve adapted to control the admission of water to said pipe, and means for urging said pipe into communication with the waste line.

7. A toilet fixture comprising a commode, a waste line therefor, a pipe extending through the commode and in inoperative position having a free end bearing against the wall of the commode, a valve adapted to control the admission of water to 10 said pipe, and means to simultaneously urge the end of said pipe into communication with the waste line and open said valve.

8. A toilet fixture comprising a commode, a waste line therefor, a line adapted to carry water under pressure in one direction, means for joining 15 said pressure line with said waste line, means for admitting water under pressure to said pressure line whereby the same may be introduced into the waste line, and means to prevent a counterflow of water.

9. A toilet fixture comprising a commode, a waste line extending from the base of the commode, a pipe extending through the commode having a free end adapted to engage the free end of the waste line when moved to operative position, 20 said pipe being in communication and carried by a rotatable pipe, a line carrying water under relatively high pressure, a valve joining said rotatable pipe and said pressure pipe, and adapted to be opened upon rotation of the 25 rotatable pipe, and a foot pedal for rotating the rotatable pipe.

10. A toilet fixture comprising a commode, a waste line therefor, a pipe extending through the commode and adapted to be oscillated, a member 40 upon the free end of said pipe adapted to form a pressure-tight seal with the waste line when the pipe is moved to operative position, a rotatable pipe in communication with said oscillating pipe and adapted to support the latter, a pipe carrying 45 water under relatively high pressure, a valve intermediate the rotatable pipe and the pressure pipe, said valve adapted to permit the flow of water from the pressure pipe to the rotatable pipe, another valve adapted to prevent the counterflow 50 of water and means for rotating the rotatable pipe whereby the valve is opened and the oscillating pipe engages the waste line.

11. A toilet fixture comprising a commode, a waste line therefor, a pipe extending through the 55 commode and adapted to be oscillated, a member on the free end of said pipe adapted to form a pressure-tight seal with the waste line when the pipe is moved to operative position, a rotatable pipe in communication with said oscillating pipe 60 and adapted to support the latter, a pipe carrying water under relatively high pressure, a valve intermediate the rotatable pipe and the pressure pipe, said valve adapted to permit the flow of water from the pressure pipe to the rotatable 65 pipe, another valve adapted to prevent the counter-flow of water and a foot pedal for rotating the rotatable pipe whereby the valve is opened and the oscillating pipe engages the waste line.

12. A toilet fixture comprising a commode, a waste line extending from the base of the commode, a pipe extending through the commode having a free end adapted to engage the free end 70 of the waste line when moved to operative posi- 75

tion, said pipe being in communication and carried by a rotatable pipe, a line carrying water under relatively high pressure, a valve joining said rotatable pipe and said pressure pipe and adapted to be opened upon rotation of the rotatable pipe, a foot pedal for rotating the rotatable pipe and spring means to return the rotatable pipe to its normal position when pressure on the foot pedal is released.

13. A toilet fixture comprising a commode, a waste line therefor, a pipe extending through the commode, means responsive to foot pressure to move said pipe to connect the same with the waste line, and spring means to move said pipe away from the waste line when foot pressure is released on said pipe.
